J. LIEBER.
LIQUID FUEL BURNER.
APPLICATION FILED JUNE 2, 1916.

1,254,145.

Patented Jan. 22, 1918.

UNITED STATES PATENT OFFICE.

JEAN LIEBER, OF LAUSANNE, SWITZERLAND.

LIQUID-FUEL BURNER.

1,254,145.

Specification of Letters Patent. Patented Jan. 22, 1918.

Application filed June 2, 1916. Serial No. 101,410.

To all whom it may concern:

Be it known that I, JEAN LIEBER, a citizen of the Republic of Switzerland, residing at Lausanne, Switzerland, have invented 5 certain new and useful Improvements in Liquid-Fuel Burners; and I do hereby declare the following to be a full, clear, and exact description of the invention, such as will enable others skilled in the art to which 10 it appertains to make and use the same, reference being had to the accompanying drawings, and to letters or figures of reference marked thereon, which form a part of this specification.

15 The present invention relates to liquid-fuel-burners for heating, welding or brazing of heavy pieces of metal lying in an open forge hearth, for which purpose, as is well known, a large flame or jet is required.

20 It has been tried to construct large burners with large flames for this purpose, but it was found that owing to their great size and weight these burners were cumbersome and difficult to handle and caused a considerable waste of heat. Thus it was found necessary to heat the pieces to be welded in an open forge hearth and to heat them simultaneously from above by means of a burner.

25 In order, however, that a burner of this kind may work satisfactorily, it should satisfy the following conditions:

(1) Combustion should take place without the development of smoke or waste of fuel 30 and should produce a maximum temperature.

(2) All means for moving the apparatus and for the control and supply of fuel must be so designed and arranged, that even after 35 several hours' continuous work they will remain cool, insure an absolutely uniform supply of fuel and besides be very durable, not giving rise to oxidation or to choking of the leads.

(3) The whole apparatus and particularly the torch itself must be adjustable to widely differing positions, so that it might be used for all kinds of work and the jet directed wherever desirable.

(4) The burner must be light in weight, ever ready for use and easily portable, so as to adapt itself to any conditions of work, be independent of the form of benches, of hearth as well as of the piece of the work 50 and dispense with the use of time-wasting arrangements for special kinds of work.

(5) The apparatus must be easy to clean and

(6) It must work to satisfaction either with fuels capable of vaporization or with 60 fuels admitting of spraying only.

The object of the present invention is to provide an apparatus of the kind described that will satisfy the above conditions.

In the accompanying drawings Figures 1 65 to 5 illustrate a first embodiment of the present invention wherein:

Fig. 1 is a perspective view of the burner,

Fig. 2 a section through the torch,

Fig. 3 a section on line A—B of Fig. 4, 70

Fig. 4 a section on line C—D of Fig. 1, and

Fig. 5 a vertical section through the fuel-can.

Fig. 6 is a section through a second example 75 of carrying the invention into effect, while

Fig. 7 shows a third embodiment of the invention in longitudinal section.

Figs. 8 and 9 are drawn on a larger scale 80 and show details hereinafter referred to.

1 is a fuel-can having a carrying handle 2 and 3 is an air pump of known design and serves to apply pressure to the fuel. 4 is a fuel-supply-pipe having a flexible part 6 and 85 a valve 5. A stand 7 is provided to carry said pipe 4 and is itself supported by arms 8 fastened to the fuel-can 1. 9 is a rod vertically guided in the said stand 7 and adapted to be fixed in any desired position by means 90 of a set screw 7^a. Slidable on the rod 9 is a sleeve 10 whose position on the former may be fixed by means of a screw 11 and which has a screw-threaded hole 12 serving as nut for the spindle of a hand-wheel 13. This 95 hand-wheel acts on a jaw 14 adapted to hold the supply-pipe 4 against the sleeve 10, whereby the said pipe can be secured in position.

Adjacent to the torch, a fuel-supply controlling device is arranged in the fuel-supply lead (Figs. 1 and 2). 16^a is a valve carried by a stem 16; the latter has a hand-wheel 17 fitted to its other end, is screw-threaded on part of its length and guided in 100 a nut 18 provided in a fitting 19. A turning movement of the hand-wheel 17 causes axial displacement of the stem 16 and the communication between the tubular passages 4 and 21 of the fitting 19 may thus be established, or interrupted, at will.

In the rear part 23 of the torch 22 is

- mounted the nozzle 24 and air admission holes 25 are provided. In order to obtain a specially easy way of cleaning the nozzle, a needle 26 is arranged and linked to a hand lever 27, which is connected to the upper part 24^a of the nozzle by means of a link having pivots at 28 and 29. A pressure on this lever 27 causes the needle 26 to move longitudinally thereby cleaning the nozzle.
- 5 At the same time, the needle 26 prevents a widening of or other injuries to the nozzle opening, and consequently a heavy wear of the nozzle. 30 is a cover around the torch 22.
- 10 A vaporization chamber 31 is arranged between the outer cover 30 and the front part of torch 22, and connected to the nozzle 24 by a tube 32^a and to the passage 21 by a tube 32. A support 33 serves to fasten the cover 30 to the fitting 19.
- 15 The apparatus works as follows: The air pump 3 is actuated until sufficient pressure is created in the fuel-can, when fuel is pressed up to the fuel-heater or vaporization chamber 31. Then the jaw 14, which in this present instance is adjustable, is loosened and the tube 4 turned until the axis of the torch takes a vertical position.
- 20 The apparatus works as follows: The air pump 3 is actuated until sufficient pressure is created in the fuel-can, when fuel is pressed up to the fuel-heater or vaporization chamber 31. Then the jaw 14, which in this present instance is adjustable, is loosened and the tube 4 turned until the axis of the torch takes a vertical position.
- 25 The apparatus works as follows: The air pump 3 is actuated until sufficient pressure is created in the fuel-can, when fuel is pressed up to the fuel-heater or vaporization chamber 31. Then the jaw 14, which in this present instance is adjustable, is loosened and the tube 4 turned until the axis of the torch takes a vertical position.
- 30 A pan or the like not shown in the drawings is arranged underneath the torch and through the nozzle 24 oil is admitted into it and ignited whereby a preliminary heating of the burner takes place and the process of vaporization is started. After removing the said pan, the whole apparatus is carried to the vicinity of the hearth on which are placed the castings to be treated, and by means of the clamping devices 7^a, 11 and 13 the torch is adjusted in any desired position.
- 35 It is clear that the supply tube 4 may be rotated about its own axis through an angle of 360° as well as swung horizontally and vertically about the universal joint at 10 through an arc of 360°. In addition its height above the floor may be adjusted at will, and the result is a heating apparatus that is always ready for work at shortest notice and that may be handled by a single operator. If so desired, the tube 4 may be
- 40 detached from the stand 7 and supported by hand. The fuel-can 1 is so arranged as to be on the side opposite to where the heating takes place, thereby at the same time acting as stabilizer to the torch which thus may be used at a considerable distance from the stand 9. The parts are distributed so as to obtain a compact apparatus that is absolutely proof against explosions and may be used everywhere, even outside the work-
- 45 shops for any length of time without any danger arising. Besides, the apparatus is easily portable and dispenses with the use of benches, supports and other auxiliary arrangements.
- 50 The clamping devices 7^a, 11 and 13 as well

as the fuel control parts 5, 17 are all at a considerable distance from the torch, are turned away from the heating point and their design preventing conduction of heat, they remain entirely cool even after several 70 hours' work, the more so as fresh air being sucked into the rear part of the torch, a current of air is generated which automatically cools the said parts. In this manner the supply of fuel is absolutely uniform, oxidation of the parts is prevented and even when the working temperature attains a maximum value, the said parts may be touched by hand without danger.

75 A further advantage of the air being admitted to the torch from behind is that this air is fresh, not yet contaminated by the hearth fire and therefore contains oxygen in a percentage sufficient for economical combustion. The controlling means also prevent ignition of the gas in the leads which may occur when shutting-off, and thus the dangerous possibility of the combustion gases gaining access to the fuel-can is definitely averted.

80 Figs. 6 to 9 show two kinds of torches which, in conjunction with the described apparatus, are intended for use with heavy oil, tar oil or other cheap fuel, and which act as atomizers.

85 In the example of execution shown in Fig. 6, the torch has a double cover 34, the inner part of which is of conical shape at one end. Between the two walls of the cover, a layer of heat-insulating material is provided at 100 35. 36 is a nozzle for the fuel, 37 a nozzle for the compressed air. It will be seen from Figs. 8 and 9 that these two nozzles are arranged at an angle, which is of 90° in the case illustrated. In this case it is also advantageous to arrange the nozzle 36 with a beveled face (Fig. 8) or with a conical bore, the axis of the cone being at an angle to that of the nozzle (Fig. 9). The result of either arrangement is that the spray of fuel issues from the nozzle in the shape of a cone whose geometrical axis is deflected, whereby a more gradual passing of the fuel into the direction of the air jet is obtained, and in this manner, the combustion is further improved. 105 As indicated in Fig. 7, in torches of this kind, the fuel nozzle may also be provided with a cleaning device of the kind shown in Fig. 2, arrangement and design of the parts being essentially as above described.

110 As the inner wall of the cover 34 becomes very hot in a short time, a quick and smoke-free ignition is obtained. On the other hand, the insulating layer 35 prevents the loss of heat, all the heat being communicated 115 to the spray of oil, while the outer wall of cover 34 serves to protect the fragile insulation against shocks so that the practical value of the apparatus is increased.

120 Referring to Fig. 7, a single cover may 130

be used and lined at 38 with a layer of suitable material such as molten quartz or the like. The torch may be exchangeable and in this case the apparatus can be used, with 5 little delay, for both light and heavy oil according to desire.

What I claim is:

1. In a liquid fuel burner, the combination with a container for fuel under pressure, of a torch, a fuel supply conduit carrying the latter and communicating with the container, a support for the conduit, and means connecting the support and conduit whereby the latter may be adjusted along a 15 vertical axis, and swing in both a vertical plane and in a horizontal plane.

2. In a liquid fuel burner, the combination with a container for fuel under pressure, of a torch, a fuel supply conduit carrying the 20 latter and communicating with the container, a support for the conduit, and means connecting the support and conduit whereby the latter may be rotated about its axis, adjusted along a vertical axis and swung in 25 both a vertical plane and in a horizontal plane.

3. In a liquid fuel burner, the combination with a container for fuel under pressure, of a torch, a fuel supply conduit carrying the latter and communicating with the container, a support for the conduit, and means connecting the support and conduit whereby the latter may be rotated about its 30 axis, moved longitudinally, adjusted along 35 a vertical axis and swung in both a vertical plane and in a horizontal plane.

4. In a liquid fuel burner, the combination with a container for fuel under pressure, of a torch, a fuel supply conduit carrying the latter and communicating with the 40 container, a vertical standard connected to the container, a connecting member adjustably mounted on the standard and compris-

ing means to adjust the conduit in angular relation to the standard and permit longitudinal displacement of the conduit. 45

5. In a liquid fuel burner, the combination with a container for fuel under pressure, of a torch, a fuel supply conduit carrying the latter and communicating with the 50 container, a vertical standard connected to the container, a connecting member adjustably mounted on the standard and comprising means whereby the conduit may be adjusted in angular relation to the standard, 55 revolved around the latter, adjusted vertically thereon, rotated on its axis, and moved longitudinally.

6. In a liquid fuel burner, the combination with a container for fuel under pressure, 60 a torch, a fuel supply conduit carrying the latter and communicating with the container, a telescopic standard connected with the latter, means for regulating the height of the standard, a sleeve adjustably 65 mounted on the upper member of the latter, a clamp rotatably mounted on the sleeve and co-operating with the latter to support the conduit in different positions.

7. In a liquid fuel burner, a torch adapted 70 to be quickly brought to a high temperature, means for protecting the torch against loss of heat, a compressed air nozzle mounted in the rear open end of the torch, a fuel nozzle arranged at an angle to the air nozzle and 75 having a conical outlet, the axis of which is at an angle to the axis of the bore of the fuel nozzle.

In testimony, that I claim the foregoing as my invention, I have signed my name in 80 presence of two subscribing witnesses.

JEAN LIEBER.
